UNITED STATES PATENT OFFICE.

JOSEPH B. STRUNK, OF MILL HALL, PENNSYLVANIA.

SILO-DOOR CONSTRUCTION.

1,309,109.

Specification of Letters Patent.

Patented July 8, 1919.

Application filed March 18, 1918, Serial No. 223,123. Renewed May 29, 1919. Serial No. 300,790.

To all whom it may concern:

Be it known that I, JOSEPH B. STRUNK, a citizen of the United States, residing at Mill Hall, in the county of Clinton and State of Pennsylvania, have invented certain new and useful Improvements in Silo-Door Constructions; and I do declare the following to be a full, clear, and exact description of the invention, such as will enable others skilled in the art to which it appertains to make and use the same.

My invention has for its object to provide an extremely simple and inexpensive, yet a highly efficient and durable silo door and locking means therefor, and with this general object in view, the invention resides in the several novel features hereinafter fully described and claimed, the descriptive matter being supplemented by the accompanying drawing in which:

Figure 1 is a front elevation of a portion of the silo embodying the present invention;

Fig. 2 is an enlarged vertical section on the plane of the line 2—2 of Fig. 1;

Fig. 3 is a horizontal section on the plane indicated by the line 3—3 of Fig. 1; and

Fig. 4 is a perspective view of one of the doors.

In the drawing above briefly described, the numeral 1 designates a silo of any preferred construction and including a pair of parallel stiles 2 and 3 whose inner edges 4 are disposed on truly radial lines so that the necessity of beveling or otherwise shaping these edges is obviated. Extending between the stiles 2 and 3 at vertically spaced points, are horizontal bars 5 and located between each pair of said bars are two doors 6, all of said doors resting one upon the other and being located on the interior of the silo, with their outer sides beveled at 7 for snug contact with the inner sides of the stiles 2 and 3 without the necessity of beveling said stiles as is commonly done. Since all of the doors 6 are identical, but one will be described in detail.

To this end, the numeral 8 designates a vertical external cleat secured to one end of the door 6 and having a beveled outer edge 9 for snug contact with the inner edge 4 of the stile 3, so that inward movement of this end of the door is prevented. An additional cleat 10 is secured vertically upon the outer side of the door 6 at its other end and is located adjacent the edge 4 of the stile 2, but need not contact therewith. Fulcrumed be-

tween its ends to this cleat 10 is a latch lever 11 having on one end a cam nose 12 to engage an abutment 13 secured to the outer side of the stile 2 in spaced relation with its edge 4, said cam also overlapping the outer side of this stile to prevent this end of the door from being forced inwardly. When the free end of the lever 11 is forced downwardly, the cam 12 so thrusts against the abutment 13 as to force the door 6 endwise to such an extent as to forcibly engage the cleat 8 with the stile 3. At the same time, an additional cam 12' on the portion of the lever opposite the cam 12, coacts with the cleat 10 to cant said lever in such a manner as to pry the adjacent end of the door outwardly into tight engagement with the inner side of the stile 2. Movement of the lever 11 to operative position also thrusts downwardly on the door 6 to an appreciable extent and thus insures snug contact thereof with the upper edge of a lower door.

By the construction and arrangement above described, the door construction may be more cheaply and easily manufactured than under the present methods, yet the door proper will be rigidly held in closed position and may be quickly and easily opened when necessary. The ladder rungs 14 are preferably secured at their ends to the cleats 8 and 10 and thus serve as handles for the doors 6 when the latter are removed. Another feature which is preferably though not necessarily employed, is the provision of a single strip 13 extending from top to bottom of the silo for coaction with the latch levers 11, but it will be understood that individual abutments could well be employed if found desirable.

From the foregoing, taken in connection with the accompanying drawing, it will be obvious that although the invention is of extremely simple and inexpensive nature, it will be highly efficient and durable for the purposes intended. Since probably the best results are obtained from the several specific details shown and described, these details are by preference employed, but within the scope of the invention as claimed, numerous minor changes may well be made.

I claim:

1. The combination of the parallel stiles of a silo, said stiles having their inner edges disposed on radial lines at right angles to their inner and outer sides, a silo door on the interior of the silo and having its outer

side beveled at its ends, said beveled ends overlapping and contacting snugly with the inner sides of said stiles, an external vertical cleat on one end of said door having a beveled outer edge at right angles to the bevel of this end of the door and contacting with the radially located edge of one of said stiles to prevent said end of the door from moving inwardly, an additional external vertical cleat on the other end of said door adjacent the other stile, an abutment on the outer side of this stile, and a vertically swinging latch lever fulcrumed between its ends to said additional cleat, said lever having on one end a cam overlapping said last named stile to hold the door against inward movement, said cam engaging said abutment

to thrust said door endwise for forcing the beveled cleat against the adjacent stile.

2. A structure as specified in claim 1, together with a second cam on the inner side of said lever in rear of its fulcrum for engagement with said additional cleat to cant the lever horizontally and thus pull the adjacent end of the door outwardly into tight contact with its respective stile.

In testimony whereof I have hereunto set my hand in the presence of two subscribing witnesses.

JOSEPH B. STRUNK.
